DESIGN FOR A CHAIR

Ermanno Galante, Woburn, Mass.

Application March 12, 1937, Serial No. 68,132

Term of patent 14 years

To all whom it may concern:

Be it known that I, Ermanno Galante, a citizen of the United States and resident of Woburn, in the county of Middlesex, State of Massachusetts, have invented a new, original, and ornamental Design for a Chair, of which the following is a specification, reference being had to the accompanying drawing, forming part thereof.

The figure is a view in perspective of a chair, showing my new design.

I claim:

The ornamental design for a chair, substantially as shown.

ERMANNO GALANTE.
